UNITED STATES PATENT OFFICE.

HENRY T. PORTER, OF PITTSBURG, PENNSYLVANIA.

RAILWAY-TRACK APPLIANCE.

SPECIFICATION forming part of Letters Patent No. 714,820, dated December 2, 1902.

Application filed December 16, 1901. Serial No. 86,023. (No model.)

To all whom it may concern:

Be it known that I, HENRY T. PORTER, of Pittsburgh, Allegheny county, Pennsylvania, have invented a new and useful Railway-
5 Track Appliance, of which the following is a full, clear, and exact description, reference being had to the accompanying drawings, forming part of this specification, in which—

Figure is a top plan view of a tie constructed
10 in accordance with my invention. Fig. 2 is an end view of the same, and Fig. 3 shows one end of the tie and a rail secured thereto by my improved fastening device.

In the drawings, 2 represent the tie, which
15 is made of metal, rolled or pressed into inverted-trough form, and at the ends portions 3 of the tie are pressed down, so as to form a connecting-bond between the two sides of the trough. The shape which is given to this connecting-bond may be serpentine, as shown, or it may be otherwise shaped. Its purpose
20 is to stiffen the tie by holding the side portions together and also to afford a resistance to prevent creeping of the tie when the tie is
25 embedded in the ballast of the track. For this purpose the device is of great advantage. The connecting-bonds being at the extreme ends of the tie, when it is desired to move the tie the ballast can easily be cleared away
30 so as to expose these portions of the tie, and thus to enable it to be free and moved. Their location at the ends of the tie also is valuable, because it adds to the strength at places where strength is greatly required.

35 In order to hold the rails to the ties, I strike up projecting lips 4 from the body of the tie, these lips being cut on three sides from the plate, so that when struck up they afford adjacent slots 5 for the bolts. The rails 6 are
40 held to the track by clips 7, which are pieces of metal, preferably rolled shape bars, and cut into sections of the desired lengths. These clips have at their inner ends beveled or recessed portions 8, which fit over the flange of
45 the rail, and an intermediate slot for the passage of the bolt 9 and for the reception of the lip 4, which projects upwardly thereinto and

bears against the side of the bolt. The bolts are preferably of hook form, and when they are applied and secured by the nuts, as shown 50 in the drawings, they coact with the clips and the lips to hold the rail firmly in place.

It is easy to adapt the clips for rails of various sizes by merely changing the location of the hole which is formed in the clip for the 55 bolt. I am thus enabled to make the clips from bars of a single size and do not need to keep in stock a large number of bars or clips to suit various sizes of rail.

Within the scope of my invention as defined 60 in the claims the construction and arrangement of the parts may be varied, since

What I claim is—

1. A metal tie of inverted-trough form with an open bottom, said tie having beneath the 65 plane of its top transverse integral connectors which extend across the trough portion and connect the sides, with a space between the connectors and the trough; substantially as described.

2. A metal tie of trough form having portions integral with the tie which extend across the trough portion thereof and connect with the sides of the tie, said connecting portions being of serpentine or zigzag form; substantially as described. 75

3. A metal tie of trough form having portions integral with the tie which extend across the trough portion thereof and connect the sides of the tie, said connecting portion being at the extreme ends of the tie and being cut apart from the body; substantially as described. 80

4. A metal tie having lips struck up from the body of the tie with adjacent slots, clips 85 applied to the rail and fitting over the lips, and bolts by which the clips are held to the tie; substantially as described.

In testimony whereof I have hereunto set my hand.

HENRY T. PORTER.
